UNITED STATES PATENT OFFICE

JAMES LUCIAN ADAMS, JR., OF EAST CHICAGO, INDIANA, ASSIGNOR OF NINE-TENTHS TO GRAVER CORPORATION, OF EAST CHICAGO, INDIANA, A CORPORATION OF ILLINOIS

METAL FABRICATING MACHINE

Application filed January 2, 1923. Serial No. 244,824.

The present invention relates broadly to the art of metal working, and more particularly to a machine adapted for the bending and fabricating of metallic shapes for the production of substantially tubular articles, although the utility of the invention is not limited with respect to the contour of the particular article produced.

The term tubular is therefore used throughout the specification and claims generically as a word of definition and not as a word of limitation, and includes within its scope hollow bodies or articles, regardless of the particular wall configuration thereof.

One of the objects of the present invention is to provide means whereby the manufacture or fabrication of tubular articles of the general character referred to can be greatly accelerated and the product turned out at a lower cost than has heretofore been possible with the usual methods of construction.

In carrying out the present invention, there is provided means for expeditiously and inexpensively assembling a hollow metal structure from a series of individual plates placed in side by side relationship and welded or otherwise secured together while in this relationship to give the desired peripheral length. The individual plate width is chosen so as to give the lowest total materials cost.

In the accompanying drawings I have shown for purposes of illustration only, one embodiment of the present invention.

In the drawings:—

Figure 1 is a view partly in side elevation, partly in section, and partly broken away, and illustrating a fabricating machine in accordance with the present invention;

Figure 2 is an end elevation of the machine shown in Figure 1;

Figure 3 is a detail view, partly in section and partly in elevation, illustrating the adjustable bearing for one end of the machine;

Figure 4 is a side elevation of one form of product produced in accordance with the present invention;

Figure 5 is a partial top plan view of the

welding table illustrating the rollers therein;

Figure 6 is a detail sectional view in a substantially vertical plane illustrating the hollow outside roll and one of the inner rolls on the welding table on opposite sides of the material being shaped; and

Figure 7 is a detail sectional view along the line VII—VII of Figure 6, looking in the direction of the arrows.

In accordance with the present invention, and referring more particularly to Figures 1 and 2 of the drawings for the present, there may be provided a fabricating machine including a movable welding table 63 1, having one or more rollers 1' adjacent its forward edge and over which the material to be formed is adapted to pass, as illustrated more particularly in Figures 5 and 7. This table is utilized as an assembly 70 table for the reception of successive new plates P, P', P², P³, P⁴, P⁵, and P⁶, and enables these plates as placed thereon to be spot-welded or otherwise secured together in side by side relationship. In Figure 75 2 of the drawings, the plates P⁵ and P⁶ are illustrated in position to be secured together, the other plates having been partly bent to formed position.

The assembly table 1 is slidably mounted 80 in a suitable base 2, positioned at one side of the machine and carried by the pedestal 3. If desired, the table 1 and the base 2 may be made in unit lengths, adapted to be coupled together at will to thereby vary the dimensions of these parts and thus accommodate them to the handling of sheets or plates of different sizes.

Positioned at any desired points in the 90 assembly table are holding-down magnets 2^a, as clearly shown in Figure 2, these magnets preferably being so positioned that the upper faces thereof are substantially flush with the supporting face of the table. 95

With plates positioned as indicated in this figure of the drawings, the holding-down magnets are effective, when energized, for holding the adjacent edges of a pair of plates in the desired position to permit the 100

same to be secured together prior to the shaping thereof.

The shaping may be accomplished by the use of a pair of spaced winding disks D, 6 which disks may comprise tank heads or other shapes which are to be incorporated in the finished article.

These winding disks are adapted to be driven through the medium of a gear train 4 cooperating with a suitable driving motor 5, under the control of the machine attendant.

In order to be able to use tank heads, for example, directly as winding disks, 15 where such heads are required in the finished article, they may be held in position by means of large electro-magnets 6 carried by the shaft 7, which is driven by the gear train 4 through the medium of a sleeve 7' surrounding the shaft and keyed thereto in such manner that axial movement between the shaft and the sleeve is permitted. Such electro-magnets will preferably, but not necessarily, be provided with a shallow depression 3', symmetrically disposed with respect to the axis of rotation of the shaft 7, and adapted to receive correspondingly shaped projections formed on the tank heads or winding disks and serving as centering 20 means therefor without the necessity of actually perforating the same. Such a centering projection may also be desirable during previous operations on the disks or heads, such, for example, as the cutting and 25 spinning operations.

The sleeve 7' is mounted for rotation in a bearing 8 carried by a sliding base 9, and adapted to be moved transversely of the axis of rotation of the shaft 7 by means of 30 a screw 10. This screw may be driven through the medium of a worm and worm wheel, as indicated in Figure 1, actuated by a suitable pinion shaft 11, having a pinion 11' secured thereto.

The driving mechanism for the gear train 4 includes a pinion shaft 12, adapted to effect axial movement of driving pinion 12'. 17-18. The parts in the full line position of Figure 1, the pinion 12' is operative for driving the gear train 4 and thereby rotating the winding disks D, while with the pinion shaft in its dotted-line position, the pinion 12' meshes with the pinion 11', so that the lead screw 10 may be rotated in one direction or the other, depending upon the direction of rotation of the motor, to thereby effect transverse movement of the sliding base 9 and its associated parts.

The different positions of the pinion shaft 12 may be suitably designated as, for example, by the letters S and M, indicating respectively the slide operating position and the machine operating position. Axial movement of the shaft 7 and its associated 25 parts, as may be required during the opera-

tion of the machine, may be obtained by means of a screw adjustment 13, cooperating with the shaft and effective for moving the same axially of the sleeve 7'.

While the bearing for the right hand end 76 of the machine as viewed in Figure 1 may be an exact duplicate of the bearing for the left hand end, as viewed in this figure, it will preferably be of the construction illustrated in Figure 3, in which parts corresponding to the parts already described are designated by the same reference characters having in each instance 100 added thereto. In this embodiment, the lead screw 110 instead of extending transversely to the axis of rotation of the shaft 7, as does the lead screw 10 indicated in Figure 2, extends longitudinally of or parallel to such axis, whereby operation of the shaft 111 through the medium of the pinion 111' will effect 80 longitudinal travel of the bearing toward or from the article being formed, sliding base 109 through the medium of the threaded projection on the sliding base through which the lead screw extends. Adjacent each of its ends, the lead screw may be of reduced diameter and unthreaded so that in the event of failure of the operator to check the operation of the motor 105 at the proper time, the lead screw will simply be unthreaded or disconnected from the sliding base, and further movement of such base will cease. 85

By means of this axial adjustment of one of the bearings, it is possible to adapt the machine to the fabrication of articles of 90 different lengths.

The assembly table 1 may be provided with a bearing extension 16 on its extreme forward end for the reception of a roller 15, as illustrated more particularly in Figure 105 5. For adjusting the assembly table toward and from the axis of rotation of the winding disks D, there may be provided a screw 17 driven through gear reduction 18 by a motor 19 under the control of the operator, 110 the motor being supported in any desired manner by the pedestal 8. This pedestal in turn may be bolted or otherwise secured to a main machine base 91.

Cooperating with the assembly table is an 115 overhead welder 22, mounted to travel on a track 23 which is in turn supported by a stiff pipe or equivalent means 24. For producing a traversing movement of the welder, there may be provided a screw 25 driven 120 through a gear reduction 26 from a motor 27. In Figure 2 of the drawings, the welder is shown in full lines in a position adapted to form the joint J between the adjacent edges of the plates P¹ and P². The welder 125 carriage, however, is preferably mounted so that it may be turned through an angle of 180° by hand, if desired, on the pivoted, flat table 28, into the position indicated, for example, in dotted lines in Figure 2, in such 130

manner that the welding electrode 29 can be brought to bear on the joint J' between the plates P⁴ and P⁵.

Secured to the base 21 opposite the pedestal 3 is a pedestal 30, carrying at its upper end a heavy, hollow outside roller 31, as illustrated in Figures 6 and 7, mounted on a non-rotating but adjustable eccentric shaft 32, carrying a worm wheel 33 actuated by a worm 34 through the medium of a crank 35.

Mounted over the roll 31, and having a free running fit with respect thereto, is a C-shaped shoe 37, carrying a short wedge 38 on its right hand lip, as shown more particularly in Figures 6 and 7. This shoe is adapted to be rotated by means of a lever 39, effective for swinging the same into such position that the right hand lip carrying the wedge 38 can be thrown downwardly into close contact with the entering plate. With the parts in this position, rotation of the winding disks through the mechanism described will be effective for directing the wedge 38 into a position under the roll 31, thereby forcing down the final edge of a plate into intimate contact with the winding disks and into a position closely adjacent the stiffening flange 40, hereinafter referred to, ready for the final welding operation.

After such operation is completed, a momentary reversal of the motors 5 and 105 will release the wedge 38 and permit it to be again thrown into the clear by means of the lever 39.

The stiffening flange 40 is preferably provided at the leading edge of the first plate P only, and is for the purpose, in all cases where it is provided, of stiffening the final joint and facilitating the formation thereof.

The rotation of the roll 31 may be retarded in any desired manner, either by the provision of a suitable brake (not shown), or by the utilization of friction bearings in such manner as to permit the placing of a considerable tension on the entering plates.

In Figure 4, there is shown one form of article which may be produced in accordance with the present invention. In this figure, the article is indicated as having incorporated therein the two winding disks D, which in this case were in the form of dished tank heads. Three plates, P, P¹, and P² are visible. As before pointed out, however, the size of the individual plates will be chosen with respect to cost, so as to keep the cost of the finished article as low as possible.

In case it is desired to form an article of this character with butt welds, it will usually be found necessary to reshear each of the plates longitudinally in order to secure sufficient joint accuracy for rapid arc welding.

If a lap weld is utilized, this preparatory expense may be obviated, but a lap weld 65 possesses the objection not only of requiring

more material and providing greater non-uniformity of wall thickness, but of also introducing offset difficulties at the line of contact between the plates and the winding disks. The additional cost of taking care of this situation in many cases more than offsets the advantages resulting from the elimination of preparatory operations of the character referred to.

In forming an article in accordance with the present invention, there is provided a supply of plates at a convenient location and height adjacent the machine, the plates having previously been subjected to the necessary preliminary shaping and sizing operations. The first plate to enter into a given new structure should preferably, for the reasons set forth, but not necessarily, be provided with a stiffening flange, which may be from four to six inches in width, depending upon the size of the article to be formed, and the thickness and characteristics of the metal. Where the flange is provided, it will, of course, be trimmed at the ends as required in order to properly clear the winding disks.

Having drawn over the first plate P from the pile, followed by the plate P', and having arranged them in proper position on the assembly table 1, they are clamped in position by the holding-down magnets 2^a and then joined together in the manner described, either by a continuous weld extending the full length of the plates, or by spot-welding, depending upon the characteristics desired in the finished product.

While the welding or other method of joining the plates is in progress, a machine operator sets the two winding disks or tank heads D, as the case may be, in proper position for the start of a new structure. The winding disks having been placed in position in the magnets 6 or other holding means provided for that purpose, they may be rotated through the mechanism provided to bring them into some predetermined, desired angular position. The pinion shift 12 may then be operated so as to adjust the bearing 8 at the left hand end of the machine in the desired position transversely of the base, the bearing at the opposite end of the machine being brought into the desired position lengthwise of the base by means of the lead screw 111. Thereafter, the holding magnet 6 at the left hand end of the machine may be axially adjusted, the forward edge of the plate P is brought to proper position with respect to the winding disks and clamped, spot-welded, or otherwise joined thereto. This having been accomplished, the respective motors 5 and 105 are operated at relatively low speeds, if of the variable speed type, or through the lowest speed gearing provided, to effect simultaneous rotation of the winding disks. This rotation effects a

feeding movement of the plates over the rolls 1' and 15 and under roll 31, the C-shaped clamp 37 and the wedge 38 being positioned at this time so as to clear the plates. This operation is continued until room is provided on the assembly table for the reception of a new plate P², which is then brought into position and secured to the trailing edge of the plate P' in the manner before referred to.

Upon completion of this operation, the motors 5 and 105 are once more started to rotate the winding disks and feed the plate P² over the rollers 1' and 15, and beneath the roller 31, in the manner before described. This operation is then repeated as often as necessary, depending upon the number of plates required, until the forward edge of the first plate P has been brought around to a point close to the under side of the projecting bearing 16 on the assembly table, at which time this table is backed away from the machine until the roller 15 clears the outer surface of the plate, whereupon the motors 5 and 105 are again started, and the winding completed. The plates are preferably so dimensioned as to allow for a slight overlap at the seam. Shortly before this winding operation is completed, the C-shaped clamp is thrown into operative position by the lever 39 so that the wedge 38 is brought into contact with the trailing portion of the last plate and advanced by the continued travel of such plate to a position under the roller 31 so that the trailing edge is forced into the desired position as before set forth. The welding head or heads 22 are now swung through an angular distance of 180 degrees in order to bring the electrode of each such welder into line with the final seam so that the adjacent edges of the plates may be joined.

If the winding disks actually comprise the tank heads or other parts to be inserted, or constitute part of the finished article, tacking on, or full length welding of the various plates to such heads, inserts, or the like, can have been progressing during the winding process, as will be apparent.

The final seam having been welded as desired, the motors 5 and 105 are backed up a slight distance to release the wedge 38 so that the C-shaped clamp can be thrown to inoperative position by the lever 39. The roller 31 is then raised a slight distance by the crank 35, after which magnets 6 may be de-energized and the screw 13 withdrawn by means of the hand wheel 14 until such time as the magnet 6 at the left hand end of the machine as viewed in Figure 1 is far enough back to clear the greatest projection on the winding disk D. At this time the pinion shifts 12 and 112 may be thrown to their slide actuating or S position, and the motors 5 and 105 operated so as to simultaneously

move the bearings at the opposite ends of the apparatus to inoperative position and thereby permit the final withdrawal of the completed structure from the machine.

In case the various parts have been spot-welded during the fabricating process hereinbefore described, they may be subsequently made gas or water tight, or stiffened, as may be desired, by the performance of subsequent operations thereon.

To those skilled in the art, it will be apparent that while I have herein disclosed and illustrated a preferred embodiment of my invention, that the drawings do not define the limits of such invention, and that changes in the construction and operation of the various parts as well as in the structural characteristics and contour of the article being fabricated may be made without departing either from the spirit of the present invention or the scope of my broader claims.

I claim:—

1. In a machine for the fabrication of tubular metal structures, an assembly table for receiving and supporting material placed thereon, welding means cooperating therewith for welding material thereon, winding means for drawing material therefrom, means for actuating said winding means to effect drawing of the material, opposed roll supports between which material may be drawn from said assembly table by said winding means, and means for adjusting the position of said assembly table toward or from the winding means in line one with the other while maintaining the same angular relationship therebetween.

2. The combination with an assembly table, of winding means, means for rotating said winding means to draw material from said table, and magnetic holding means cooperating with said table for holding material in position thereon.

3. The combination with a table for assembling tubular structures, of winding means including a series of axially spaced heads adapted to be incorporated in the finished structure, means for rotating said winding means to draw material from said table, holding means cooperating with said table, and means for adjusting the position of said table toward or from said winding means.

4. In a machine of the character described, magnetic means for holding winding disks, means for rotating said magnetic means to effect rotation of winding disks carried thereby, and means for effecting axial adjustment of one of said magnetic means toward or from the other magnetic means.

5. In a machine of the character described, magnetic means for holding winding disks, means for rotating said magnetic means to effect rotation of winding disks

carried thereby, and means for effecting axial adjustment of both of said magnetic means.

6. In a machine of the character described, means for rotating a pair of axially spaced winding disks to effect the positioning therearound of material to be shaped, welding means for forming such material from a plurality of individual sections, and 10 means for clamping the trailing edge of the material against the winding disks.

7. In a machine for the fabrication of tubular metal structures, an assembly table for receiving and supporting plates placed 15 thereon, means cooperating with the assembly table for joining together adjacent plates on said table, winding means including spaced heads adapted to receive plates from said assembly table and adapted to be incorporated 20 in the finished structure and around which the assembled plates are wound, and means for rotating said winding means to effect a feeding movement of the joined plates from the assembly table 25 around said heads.

8. In a machine for the fabrication of tubular metal structures, an assembly means including a table on which successive plates are adapted to be placed and joined, a winding means for withdrawing plates from said table and shaping the same, and clamping means for clamping the trailing end of a plate against said winding means.

9. In a machine for the fabrication of tubular metal structures, assembly means for receiving and supporting plates placed thereon, said assembly means providing an end roller over which the plates are adapted to travel, means cooperating with the assembly means for joining together plates placed thereon, winding means cooperating with said assembly means for winding the assembled plates from the assembly means, and means for rotating said winding means 45 to effect a feeding movement of the joined plates over said end roller from the assembly means around the winding means.

10. In a machine of the character described, a pair of rotatable heads adapted 50 to detachably receive a pair of winding discs, an assembly table disposed at one side of the heads and discs, having portions adjacent said discs disposed tangentially thereof for supporting material in position laterally of the discs to be fed thereto, and means for clamping the material at will against said discs.

11. In a machine of the character described, a pair of rotatable chucks adapted 60 to receive a pair of winding disks, a roller having an axis of rotation parallel to the axis of rotation of said chucks, means for feeding material to be shaped between such disks and said roller, and means for clamping 65 material in position therebetween.

12. In a machine of the character described, a pair of rotatable chucks adapted to receive a pair of winding disks, a roller having an axis of rotation parallel to the axis of rotation of said chucks, means for feeding material to be shaped between such disks and said roller, and means for clamping material in position therebetween, said last mentioned means including a clamp adjustable about the axis of said roller. 70 75

In witness whereof, I hereunto subscribe my name.
